(57) **CLAIM**

The ornamental design for self-retracting lifeline housing, as shown and described.

DESCRIPTION

FIG. 1 is a front view of a self-retracting lifeline housing;

FIG. 2 is a rear view of the self-retracting lifeline housing shown in FIG. 1;

FIG. 3 is a top view of the self-retracting lifeline housing shown in FIG. 1;

FIG. 4 is a bottom view of the self-retracting lifeline housing shown in FIG. 1;

FIG. 5 is a left side view of the self-retracting lifeline housing shown in FIG. 1;

FIG. 6 is a right side view of the self-retracting lifeline housing shown in FIG. 1; and,

FIG. 7 is a perspective view of the self-retracting lifeline housing shown in FIG. 1.
